UNITED STATES PATENT OFFICE.

SIEGMUND SALOMON, OF NEW YORK, N. Y.

DESIGN FOR A FURNITURE-BUFFER.

SPECIFICATION forming part of Design No. 33,498, dated November 6, 1900.

Application filed October 11, 1900. Serial No. 32,795. Term of patent 7 years.

To all whom it may concern:

Be it known that I, SIEGMUND SALOMON, a citizen of the United States, and a resident of the city of New York, borough of Manhattan, 5 in the county and State of New York, have invented and produced a new and original Design for a Furniture-Buffer, of which the following is a full, clear, and exact description.

Reference is to be had to the accompanying 10 drawings, forming a part of this specification, in which—

Figure 1 is a perspective view of a furniture-buffer embodying my design, and Fig. 2 is an edge view.

15 The leading feature of my design for a furniture-buffer consists in a circular body por-

tion, at one side of which is a central semi-spherical projection, and extended from the edge at the opposite side are tooth-like structures.

Having thus described my invention, I claim as new and desire to secure by Letters Patent—

The design for a furniture-buffer, as herein shown and described.

In testimony whereof I have signed my name to this specification in the presence of two subscribing witnesses.

SIEGMUND SALOMON.

Witnesses:

EVERARD BOLTON MARSHALL,
F. W. HANAFORD.
